PNEUMATIC VIBRATOR FOR DETECTING RATTLES

Robert E. Barrows, Frankfort, N.Y., assignor to Chicago Pneumatic Tool Company, New York, N.Y.

Filed Nov. 9, 1971, Ser. No. 197,192

Term of patent 14 years

Int. Cl. D15—99

U.S. Cl. D55—1 D

FIG. 1

FIG. 2

FIG. 3

FIG. 4

FIG. 5

FIG. 7

FIG. 6

FIG. 1 is a side elevational view of a pneumatic vibrator for detecting rattles showing my new design;

FIG. 2 is an elevational view of the right end of FIG. 1;

FIG. 3 is an elevational view of the left end of FIG. 1;

FIG. 4 is an elevational view of the side of the rattle detector opposite to that shown in FIG. 1;

FIG. 5 is a top plan view of FIG. 1;

FIG. 6 is a bottom plan view of FIG. 1; and

FIG. 7 is a section taken on line 7—7 of FIG. 1.

I claim:

The ornamental design for a pneumatic vibrator for detecting rattles, as shown and described.
